UNITED STATES PATENT OFFICE.

ALLAN R. HODGES, OF CHICAGO, ILLINOIS, ASSIGNOR OF ONE-HALF TO CYRUS A. McALLISTER, OF MEMPHIS, TENNESSEE.

FEED-WATER HEATER FOR LOCOMOTIVE-BOILERS.

1,335,439.

Specification of Letters Patent. Patented Mar. 30, 1920.

Application filed January 12, 1918. Serial No. 211,636.

To all whom it may concern:

Be it known that I, ALLAN R. HODGES, a citizen of the United States, residing at Chicago, in the county of Cook and State 5 of Illinois, have invented new and useful Improvements in Feed-Water Heaters for Locomotive-Boilers, of which the following is a specification.

This invention relates to improvements in 10 feed water heaters for steam boilers, more especially intended for use in connection with locomotive boilers.

The principal objects of the invention are to provide a feed water heater which shall 15 raise the temperature of the feed water to a considerably greater degree than is possible with any of the feed water heating arrangements for locomotive boilers heretofore proposed; which shall effectively utilize 20 the heat of the waste gases of combustion without impairing the draft; which shall be so arranged that its installation does not entail any change whatever in the structure or disposition of the smokebox inclosed

25 parts and will permit of the said parts being constructed and arranged, as heretofore, in accordance with the type of locomotive desired; which shall not interfere with the usual arrangement for supplying feed water

30 to the boiler, thereby rendering such arrangements available in an emergency; which may, if desired, or necessary in an emergency be cut off from, and therefore rendered independent of the boiler and feed

35 water supply system; which may be as readily applied to locomotives in service as to those in course of construction; which may be constructed in the shop independently of the boiler, and may be installed or 40 removed with facility and in a very short time; and which shall be of simple structural character and relatively inexpensive to manufacture and install.

With the above objects in view the invention, generally stated, consists in a feed water heater in association with the smokebox whereby the waste gases of combustion, which, in all cases, have a relatively high fuel efficiency are diverted and utilized prior 50 to their discharge into the atmosphere; and in connection with a feed water heater having the above essential characteristics the invention also consists in certain features of structure, combination and relation involving 55 details of the feed water heater and

of its relation to the smokebox, as will be set forth at length in the succeeding description.

An embodiment of the invention is illustrated in the accompanying drawings, 60 wherein:

Figure 1 is a vertical longitudinal section showing a feed water heater in which the features of the invention are incorporated and its operative relation to the smokebox 65 and the front portion of the boiler of a standard locomotive.

Fig. 2 is a view partly in transverse section on the line 2—2 of Fig. 1 and partly in front elevation.

Fig. 3 is a plan view in half of which the outer shell has been omitted to show the internal radiating arrangement of the tubes through which the waste gases pass from the smokebox.

Similar characters of reference designate corresponding parts throughout the several views.

The invention is applicable to any standard type of locomotive and its installation 80 does not in any way interfere with any desired arrangement or structure of the smokebox inclosed parts.

The invention is shown as applied to a well known type of locomotive having its 85 smokebox A located, as usual, in front of the boiler B. Figs. 1 and 2 show in broken lines the usual smokebox inclosed parts, viz. the dry-pipe fitting C, the diaphragm D, the engine exhaust E, the petticoat-pipe F and 90 the smokestack lift-pipe G.

The shell of the smokebox is utilized throughout its upper portion as the inner shell 1 of the casing of the feed water heater, the said casing also including an outer shell 95 2, a front plate or head 3 and a rear plate or head 4.

The outer shell is arranged transversely over the shell 1 with which, in the embodiment disclosed, it forms a crescent shaped 100 inclosure and is provided along its sides with off-set terminal flanges 5 which serve for its attachment, preferably by means of rivets 6, to the shell 1. The heads 3 and 4 conform to the cross-sectional outline of the 105 inclosure formed by the shells 1 and 2 and are provided at their upper ends with in-turned flanges 7 which are secured, preferably by welding, to the transverse edges of the shell 2, and at their lower ends with 110

out-turned flanges 8 which are secured by rivets 9 to the shell 1. In the embodiment disclosed the flange 8 of the head 3 partly circumscribes the front smokebox ring H 5 and the flange 8 of the head 4 partly circumscribes the front edge portion of the boiler shell.

The casing of the feed water heater is completed by an open ended cylinder 10 10 which preferably has a slight upward flare and has the same location as the usual smokestack whose place it takes. The cylinder 10 is provided along its upper and lower edges with circumscribing flanges 11 which are secured, preferably by welding, to the respective shells 1 and 2. As a means of protection for the cylinder 10 at its jointure with the shells, rings 12 and 13 are fitted over the respective upper and lower ends of said 15 cylinder, said rings being secured to the shells preferably by rivets. The lower ring 13 forms, in effect, an extension of the usual smokestack lift-pipe G.

For bracing and strengthening purposes 20 transverse bars 14 are suitably arranged against the outer faces of the heads 3 and 4, the correspondingly located bars on the two heads being held in place by tie-rods 15 which are located internally and externally 25 of the feed water heater.

The shells 1 and 2 may also be braced to one another by any suitable arrangement of radial stays whose illustration is unnecessary 30 since the prior art features may be utilized in this regard, the construction and arrangement shown in my Patent No. 1,249,958, granted December 11, 1917, being preferably 35 employed.

The feed water heater is preferably 40 divided interiorly into a front compartment 16 and a rear compartment 17 by means of a transverse partition 18; and in order that water may pass from the front compartment to the rear compartment and may have an 45 effective circulation in the rear compartment it is preferred to employ a pipe 19, connected near the upper edge of the partition 18, and arranged in the rear compartment, said pipe following the curve of the outer shell to a 50 point near the lowest point of the compartment where it is provided with an angular or upturned discharge terminal.

The fuel value of the gases of combustion is utilized by a relatively large number of 55 heating tubes 20 which extend between the shell 1 and the cylinder 10 and through which the gases are passed from the smokebox to the interior of the cylinder 10 by which they are discharged into the atmosphere. The tubes 20 are arranged radially 60 with reference to the cylinder 10 at regular intervals throughout its circumference and, having relatively small diameters, are preferably disposed in parallel or concentric 65 courses or tiers, the ends of the tubes being

suitably fitted in openings provided therefor in the shell 1 and cylinder 10. The number of courses or tiers of tubes 20 should be such as to best utilize the areas of the cylinder 10 and shell 1 available for the attachment of said tubes. It is obvious that by providing a relatively large number of relatively narrow tubes for the passage of gas from the smokebox to the interior of the cylinder 10 advantages are secured in that the draft will not be impaired, the aggregate heating surface for the water is relatively large, and the heat or fuel value of the waste gases is most effectively utilized.

The usual boiler feed pipe is connected to 70 an extension feed pipe 21 which, by means of an injector (not shown) operating in the usual manner, supplies the feed water heater, the pipe 21 being connected with the chamber 16 of the feed water heater by an inlet 75 check 23 of the usual construction. The pipe 21 is preferably provided with a globe or other suitable valve 21^a by which the feed water heater may, if found necessary or desirable, be rendered independent of the boiler 80 and of the feed water system, as in case of an injury to the feed water heater while the locomotive is in service, i. e., making a run, or in connection with the cleaning of the feed water heater. If, while the feed water 85 heater is thus cut off by the valve 21^a, it should be necessary to supply the boiler with feed water this can be done in the usual manner, the boiler feed pipe being provided, beyond the pipe 21 with the usual boiler 90 valve and check 22.

By virtue of the provision of the chambers 16 and 17 the water is heated in two stages, its initial heating in the chamber 16 being effected by those gases which, owing 105 to their proximity to the cold front plate of the locomotive, are of the lowest heat or fuel value, and its subsequent heating in the chamber 17 being effected by those gases whose heat or fuel value is greatest. The heated feed water is conducted from the heater to the boiler by a pipe 24 which, adjacent the feed water heater, is provided with a suitable outlet check 25. The elevation of the point of communication of the 110 pipe 24 with the feed water heater is selected to insure that a considerable quantity of water shall always remain in the heater.

The pipe 24 preferably discharges upon a splash plate 24^a suitably supported in the 115 boiler and provided as a means of protection to the boiler tubes or flues, directly under the discharge end of the pipe 24, this plate causing the water to splash in all directions as it falls into the steam space.

The outer shell 2 is preferably provided with a safety valve 26 for relieving any excessive steam pressure which may be developed in the feed water heater. The said heater is also provided with a suitable blow- 120

off cock 27 and with suitably arranged wash-out plugs 28, which may be removed when the heater is to be cleaned, this being effected by suitable washing out operations.

- 5 It is obvious that the feed water heater, constructed as above described, will suffer the ill effects of the scale forming properties of bad water and will, therefore, provide a substantial measure of protection for
10 the boiler. The lodgment of scale or deposit within the feed water heater does not, however, constitute any serious disadvantage to the heater because of the facility with which its interior may be cleaned by
15 virtue of the wash-out plugs 28 and also because the crescent-shape form of the heater causes the precipitated solid matter to settle into the pockets (provided by the depending "horns" of the crescent) in whose outer
20 walls the plugs 28 are arranged.

The present invention, by virtue of the principles of structure and operation described effectively reclaims and utilizes a large percentage of the heat which is ordinarily wasted with the discharged gases of combustion and is calculated to represent a waste of about thirty per cent. of the fuel efficiency. By means of the present feed water heater all of the water supplied to
25 the boiler may be readily pre-heated to temperatures ranging from 250° to 350° F.

Having fully described my invention, I claim—

1. A feed water heater for locomotive
35 boilers comprising a casing arranged in external association with the boiler smokebox and having a feed water inlet and outlet, said casing utilizing as its inner shell the shell of the smokebox and having an outer
40 shell arranged transversely over the inner

shell and end heads extending between said shells, the shells forming a crescent-shaped inclosure, an open ended cylinder extending between said shells, said cylinder taking the place of the usual smokestack, and a plurality of open ended tubes arranged radially of said cylinder at regular intervals throughout its circumference, and disposed in courses or tiers, said tubes extending through the casing between the smokebox 50 and the cylinder and serving to conduct the gases of combustion into said cylinder and to effect the heating of the water in said casing.

2. A feed water heater for locomotive 55 boilers comprising a casing provided with a feed water inlet and outlet and having a crescent shaped cross-section which conforms to the curvature of the smoke box shell, the said casing being in external association with the upper side of the boiler smokebox, a cylinder extending through said casing and open to the smoke box and to the atmosphere, said cylinder taking the place of the usual smoke stack, and a plurality of open ended tubes extending 60 through said casing and between the smoke box and the cylinder to conduct gases of combustion into the cylinder and to effect the heating of the water in said casing, said 65 tubes thereby being subject to atmospheric draft.

In testimony whereof I have hereunto set my hand in presence of two subscribing witnesses.

ALLAN R. HODGES.
